UNITED STATES PATENT OFFICE.

JOHN GARDULIZ, OF SONMAN, PENNSYLVANIA, ASSIGNOR OF ONE-THIRD TO
NIKOLAI LUTZIUK, OF SONMAN, PENNSYLVANIA.

RAIL CONNECTION.

1,402,158.

Specification of Letters Patent. Patented Jan. 3, 1922.

Application filed May 7, 1921. Serial No. 467,674.

To all whom it may concern:

Be it known that I, JOHN GARDULIZ, citizen of Russia, residing at Sonman, in the county of Cambria and State of Pennsylvania, have invented certain new and useful Improvements in Rail Connections, of which the following is a specification.

This invention relates to a novel and improved construction for the joints of track rails and it has for an object to provide a simple and inexpensive arrangement of parts for securing together the adjacent rail ends.

A further object is to provide a rail joint in which the usual bolts and nuts are dispensed with, thereby reducing liability of loosening of the joint.

For further comprehension of the invention, and of the objects and advantages thereof, reference will be had to the following description and accompanying drawings, and to the appended claims in which the various novel features of the invention are more particularly set forth.

Fig. 1 of the drawings is a plan view showing the adjacent rail ends as constructed according to my invention, the rail ends being slightly separated.

Fig. 2 is a side view of the parts as shown in Fig. 1, showing also a portion of the roadbed in section.

Fig. 3 is an underside plan view showing the rail ends joined and the locking pin in position, the operative position of the retaining plate being indicated in dotted lines.

Fig. 4 is a transverse section on the line 4—4 of Fig. 3.

Fig. 5 is a similar view to Fig. 1, but showing a modified form of the invention.

Figs. 6 and 7 are similar views to Figs. 1 and 2 respectively showing a further modification.

In the drawings the numerals 10 and 11 respectively indicate adjacent track rails whose main lengths are of usual construction, these rails resting on the usual ties 13. In the form shown in Figs. 1 to 4 the rail 11 is tapered at its end to wedge shape as at 14, while the rail 10 is formed with a complementary recess 15 adapted to receive this tapered end. This taper 14 is formed only in the web 11' and foot 11^a of the rail, the tread 11^b being cut off square at the point where the taper commences.

Similarly the recess 15 does not extend

through the tread 10^b of the rail 10, this tread being carried forward unbroken to abut against the tread 11^b of rail 11. The web 11' is longitudinally and vertically slotted as at 16 from the end of the tread 11^b 60 forwardly to the extreme point of the tapered rail end, this slot extending downwardly through the foot of the rail, while the web 10' of the rail 10 is extended forwardly but with diminished thickness as at 10^c through the recess 15 to the end of the tread 10^b, the thickness of this forward portion of the web corresponding to the width of the slot 16.

In one wall of the slot 16 a vertical groove 70 17, preferably of rectangular cross section, is formed, while a complementary groove 18 is formed in the corresponding wall of the web portion 10^c, these grooves registering and jointly forming a square socket when the 75 rail ends are pushed together as clearly shown in Fig. 3. Into the socket thus formed is inserted upwardly a square pin 20.

This pin 20 is prevented from being displaced by a plate 21 which may be slidably 80 carried on the underside of either of the rails and is moved along the rail to a position under the engaging rail ends, as indicated in dotted lines in Fig. 3, the body of the plate lying in close contact with the foot 85 of the joined rails while the plate is provided with hook-like flanges 22 at the sides which engage over the edges of the foot of the adjacent rail ends and hold the plate against displacement, while, as will be obvious 90 the plate serves also to brace the rail end joint.

Formed in the flanges 22 on the plate 21 are recesses 23 which are adapted to receive the heads of spikes which may be driven into a tie placed under the rail joint, longitudinal displacement of the plate 21 being thus prevented. The underside of the plate may have transverse recesses 23' formed therein which, in cases where the rail joint is set in 100 concrete, will receive the same and so act to hold the plate against longitudinal movement.

In the modification shown in Fig. 5 the construction corresponds in the main to that 105 already described. In this case however, the wedge-shaped end and correspondingly shaped socket are omitted, the web and foot of the rail 11 being continued beyond the tread and cut off square, and the web and 110

foot of the rail 10 being correspondingly cut off. The web 11' may have a pair of projections 25 which engage in corresponding recesses 26 in the web 10'.

- 5 In the modification shown in Figs. 6 and 7 the rail ends are cut off similarly to the rail ends shown in Fig. 5. In this construction, however, the pin 20 is not employed, while the slot 16' in the projecting web does 10 not extend to the bottom thereof, the bottom wall of this slot having a rectangular aperture 27 extending therethrough, the web 10' of the rail 10 having a lug 28 on its bottom adapted to engage in this aperture when the parts are assembled.

Having thus described my invention what I claim as new and desire to protect by Letters Patent of the United States is as follows:

- *20 1. In a device of the class described, a pair of cooperating rail ends one of which has the web and foot thereof tapered and extending beyond the tread of the rail, the web and foot of the other rail end having 25 a complementary recess adapted to receive the said tapered extension, said rail ends each having a socket half formed therein and jointly forming a socket, and a locking pin inserted in said socket.
- 20 2. In a device of the class described, a pair of cooperating rail ends one of which has the web and foot thereof tapered and extending beyond the tread of the rail, the web and foot of the other rail end having 35 a complementary recess adapted to receive the said tapered extension, said rail ends each presenting a portion of a vertically split socket, and a locking pin inserted into said socket.
- 40 3. In a device of the class described, a pair of cooperating rail ends one of which has the web and foot thereof tapered and extending beyond the tread of the rail, the web and foot of the other rail end having 45 a complementary recess adapted to receive the said tapered extension, said rail ends each presenting a portion of a vertically split socket, a locking pin inserted upwardly into said socket, and a plate slidable on the 50 foot of the rail and adapted to prevent displacement of said pin from said socket.
- 50 4. In a device of the class described, a pair

of cooperating rail ends one of which has the web and foot thereof vertically and longitudinally slotted, the opposite end having the web and foot thereof formed to extend into said slot, the walls of said slot and of the last mentioned web being each vertically slotted to present jointly a socket extending upwardly from the bottom of the 55 rail, a locking pin inserted upwardly into said socket, and a plate slidable on the rail adapted to prevent displacement of the said pin.

5. In a device of the class described, a 60 pair of cooperating rail ends one of which has the web and foot thereof vertically and longitudinally slotted, the opposite end having the web and foot thereof formed to extend into said slot, the walls of said slot 65 and of the last mentioned web being each vertically slotted to present jointly a socket extending upwardly from the bottom of the rail, a locking pin inserted upwardly into said socket, and a plate slidable on the 70 rail adapted to prevent displacement of the said pin, said plate having recesses in the top thereof adapted to receive the heads of spikes, for the purpose set forth.

6. In a device of the class described, a 80 pair of cooperating rail ends one of which has the web and foot thereof tapered and extending beyond the tread of the rail, said extended portion being longitudinally slotted, the web and foot of the other rail being 85 formed with a recess adapted to receive the said tapered extension and having a central member adapted to project into the said slot, the walls of said slot and of said central member being each vertically slotted to present jointly a socket extending upward from the bottom of the rail, a locking pin inserted upwardly into said socket, and a plate on the rail adapted to prevent displacement of the 90 said pin, said plate having hooked side 95 flanges adapted to engage the foot of the rail.

In testimony whereof I have affixed my signature.

JOHN ^{his} GARDULIZ.
